Specification for Design.

Patented May 16, 1911.

Application filed March 18, 1911. Serial No. 615,444. Term of patent 7 years.

To all whom it may concern:

Be it known that I, WALTER M. GRATE, a citizen of the United States, residing at Ceredo, in the county of Wayne and State of West Virginia, have invented a new, original, and ornamental Design for Penholders, of which the following is a specification, reference being had to the accompanying drawing, forming part thereof.

Figure 1 represents a top plan view of the pen holder. Fig. 2 represents a left side elevation thereof. Fig. 3 represents a similar view of the other side, and Fig. 4 represents a bottom plan view of the pen holder.

I claim:

The ornamental design for a pen holder, as shown.
